UNITED STATES PATENT OFFICE.

WILLIAM R. COLMAN, OF QUINCY, ILLINOIS.

BALING-PRESS.

SPECIFICATION forming part of Letters Patent No. 727,907, dated May 12, 1903.

Application filed September 17, 1902. Serial No. 123,790. (No model.)

To all whom it may concern:

Be it known that I, WILLIAM R. COLMAN, a citizen of the United States, residing in Quincy, in the county of Adams and State of Illinois, have invented certain new and useful Improvements in Baling-Presses, of which the following is a full, clear, and exact description, reference being had to the accompanying drawings, forming part of this specification.

My present invention relates to the same general character of a baling-press as those shown and described in my Patents Nos. 671,940, 675,197, 678,941, and 682,240, issued, respectively, on April 9, 1901, May 28, 1901, July 23, 1901, and September 10, 1901; and the objects of my present improvements are to provide for a quick preliminary forward movement of the traverser, also to provide an improved form of brake mechanism to retard the backward movement of the traverser, and also to provide a simple and effective mechanism for operating the feeder of the press.

My present invention consists in features of novelty hereinafter fully described, and pointed out in the claims.

Figure I is a detail top or plan view of the power end of my improved press, the sweep-shaft being shown in section. Fig. II is a detail elevation showing the power end of the press, the supporting axle or shaft being shown in section. Fig. III is an enlarged detail horizontal section showing the brake mechanism, this section being taken on line III-III, Fig. IV. Fig. IV is a vertical section of the brake mechanism, taken on line IV-IV, Fig. I. Fig. V is a detail side view, part in section, showing the upper end of the baling portion of the press. Fig. VI is a detail section taken on line VI-VI, Fig. V. Fig. VII is a detail view of the feeder looking in the direction of the arrow, Fig. V.

Referring to the drawings, 1 represents the pitman of the press, having an outer head 2 and the inner end of which is connected to the plunger or traverser of the press at 3, as shown by dotted lines in Fig. V.

4 represents the reach of the press, the outer end of which connects with a casting or bed-plate 5, supported by one of the wheel-axles 6 of the press, the other end of the reach

being made fast to the baling-chamber 7, as shown at 8.

9 is the sweep-head of the press, made fast, 55 as usual, to a vertical shaft 10, suitably mounted on the casting or bed-plate 5—as, for instance, in the manner shown and described in my Patent No. 675,197, 11 in this application indicating the frame or yoke 9 of the 60 patent last mentioned.

12 represents the cross-head of the press, secured to the shaft 10 and provided with friction-rollers 13 at its ends. As in the patents referred to, the rollers 13 move along the 65 longitudinal face of the head 2 of the pitman until the latter reaches a certain position in its forward movement, and then the rollers come against the end of the head 2, forcing the pitman forward to effect the final pressure 70 on the plunger. One of the objects of my present invention is to obtain a long and quick preliminary forward movement of the pitman, and this I accomplish by connecting the inner ends of the links 14 (which correspond to the links 13 of my Patent No. 682,240) to a lever 15, the outer ends of the links 14 being connected to a lateral projection 16 on the head 2. The outer end of the lever 15 has a pivotal connection with links 17 at 18, 80 while the inner end of the lever is rounded off to receive the impact of the rollers 13 of the cross-head 12. The inner ends of the links 14 are pivoted to the lever 15 at 19, which is between the inner end of the lever 85 and the pivot 18 thereof. The outer ends of the links 17 are pivoted at 20 to the outer part of the yoke or frame 11. As the cross-head 12 is turned the nearest roller 13 comes against the lever 15, and by swinging the lever on its 90 pivot 18 and the links 17 on their pivot 20 the pitman is caused to be drawn forward with a quick movement, the other roller 13 at this time bearing upon the longitudinal inner face of the head 2 of the pitman. As the pitman 95 reaches a certain position in its forward movement, which is near the end of its stroke, the roller 13, which has been riding on the longitudinal face of the head 2, passes around against the end of the head 2, as shown by 100 dotted lines, Fig. I, and the final pressure on the pitman and plunger is exerted by a direct push of the cross-head against the end of the pitman. When the roller 13 leaves the head

of the pitman, the parts will rebound from the position shown by dotted lines in Fig. I to the position shown by full lines, in which position they are ready to effect the next forward movement of the plunger as the roller 13 comes against the lever 15.

21 represents the carrier-arm of the press, which corresponds to the carrier-arm 20 of my Patent No. 682,240. The pitman rests 10 upon this arm and causes it to be moved forward from the position shown in full lines, Fig. I, to the position shown in dotted lines as the plunger is advanced in the operation 15 of the press. The carrier-arm is pivoted to the casting 5, as shown in Fig. IV, the casting having a circular projection 22 to receive a socket or hole formed in the carrier-arm, the arm being held to the casting by means of a bolt 23 and a washer 24, the bolt passing 20 through the washer and the casting or bed-plate 5. The carrier-arm is thus free to revolve or turn on the projection 22. As stated, the arm is moved forward by the forward movement of the pitman, owing to the frictional contact between the two, and when the 25 final pressure is exerted on the pitman and the cross-head leaves the head 2 of the pitman the latter rebounds, and the carrier-arm acts as a check to cushion the rebound of the 30 pitman, this action of the arm being effected through means of a brake-shoe 25, pivoted at 26 to the carrier-arm and the concave inner face of which bears against a fixed face 27 on the casting or bed-plate 5. The shoe 25 is 35 backed up by a coil-spring 28, located in a housing 29, formed on the under side of the carrier-arm, and back of the spring is a set-screw 30 for adjusting the tension of the spring so that the pressure of the brake-shoe 40 against the bed-plate 5 may be regulated as conditions may require. The outer end of the carrier-arm is provided with a lug or ear 31, corresponding to the lug or ear 23 of my Patent No. 678,941.

45 32 represents the feeder-arms of the press, used for the purpose of forcing the charges of material into the baling-chamber, these arms being secured to a rock-shaft 33, journaled in boxes 34, secured to the upper face 50 of the inner end of the baling-chamber, as shown in Fig. V. In order that the feeder-arms may be wholly outside of the hopper 35 of the press when the charges are being thrown into the hopper, I locate the shaft 33 55 a short distance back of the hopper and form slots 36 in the end of the hopper, through which the arms pass when they are operating, these slots 36 being shown in Figs. VI and VII. To the end of the hopper 35 I 60 secure brackets 37, which receive and hold the feeder-arms when in their upper positions and act to guide the arms to the slots 36. The feeder-arms are moved from the position 65 shown in full lines, Fig. V, to the position shown in dotted lines by means of the sweep-head, this being effected by means of a crank 38, secured to one end of the rock-shaft 33

and to which is connected one end of a cord or cable 39, that passes under a pulley 40, journaled to the baling-chamber, the other 70 end of the cable being connected to a lever 41, that is pivoted at 42 to a block 43, made fast to the brace-rod 44 of the press. The inner end of the lever 41 is curved, as shown at 45, Fig. I, and this end of the lever is in the path 75 of projections (preferably in the form of friction-rollers) 46, that depend from the under side of the sweep-head 9. As the pitman advances and during the first part of its forward movement one of the projections 46 comes 80 against the lever 45 and through means of the described connection between this lever and the feeder-arms causes the latter to be moved downwardly from the position shown in full lines in Fig. V to the position shown 85 in dotted lines, thus causing the charge to be forced from the hopper into the baling-chamber of the press. When the sweep-head leaves the lever 45, the feeder-arms are returned to their normal positions by means of a spring 47, connected at one end to the baling-chamber of the press and at the other end to a crank-arm 48, secured to the rock-shaft 33. The cord or cable 39 is connected to the crank 38 by means of a clevis 49, the bolt of 90 which fits in a curved slot 50, formed in the crank. The effect of this is that during the first part of the movement of the feeder-arms a quick motion is imparted thereto, whereas during the final movement of the arms a slow 95 and more powerful force is exerted on the arms by virtue of the point of connection between the clevis and the crank moving farther from the rock-shaft 33, which is the pivotal point about which the feeder-arms move. 100 The feeder-arms are straight throughout the main portions of their lengths, but at their outer ends 51 are curved inwardly, the result being that as the feeder-arms move downwardly their main portions exert a downward 105 movement on the material, while their outer ends tend to draw the charge of material 110 forwardly out of the hopper into the baling-chamber.

It will be observed that the outer end of 115 the pitman-head is formed on an incline and the outer corner of the head is provided with a friction - roller 60. By forming the outer end of the head with an inclination the cross-head draws the pitman inwardly as one of its 120 rollers engages the outer end of the head of the pitman, and by providing the roller 60 there is no danger of the end of the cross-head passing around the outer corner of the pitman - head, for the roller 60 will come 125 against the roller on the end of the cross-head and prevent any further lateral movement of the end of the pitman after the roller 60 comes against the roller 13.

I claim as my invention—

1. In a baling-press, the combination of a pitman, a cross-head adapted to engage a head on the pitman, links pivoted to the head on the pitman at one end, a lever to which the

other ends of the links are pivoted and which is adapted to be engaged by said cross-head, and a link to one end of which said lever is pivoted and which is pivoted at its other end 5 to a fixed point, substantially as set forth.

2. In a baling-press, the combination of a pitman, a cross-head adapted to engage a head on the pitman, links pivoted at one end to a projection on the head of the pitman, a lever 10 to which the other ends of the links are pivoted and which has a rounded end adapted to be engaged by said cross-head, and a link to one end of which said lever is pivoted and which is pivoted at its other end to a fixed 15 point, substantially as set forth.

3. In a baling-press, the combination of a pitman, a carrier-arm upon which the pitman rests, a bed-plate to which the carrier-arm is pivoted, and a brake for said carrier-arm consisting of a shoe pivoted to the arm, and a 20 spring for pressing said shoe against said bed-plate, substantially as set forth.

4. In a baling-press, the combination of a pitman, a carrier-arm upon which the pitman rests, a bed-plate to which the carrier-arm is pivoted, and a brake for retarding the movement of the carrier-arm, consisting of a shoe 25 having a concave face adapted to bear against a convex face on said bed-plate and a spring to press the shoe against the bed-plate, substantially as set forth.

5. In a baling-press, the combination of a pitman, a sweep-head, a plunger carried by the pitman, feeder-arms, and means for moving the feeder-arms, consisting of a pivoted 30

lever to which the arms are connected and which is adapted to be engaged by projections on said sweep-head, substantially as set forth.

6. In a baling-press, the combination of a pitman, a plunger connected to the pitman, 40 a sweep-head, feeder-arms, a rock-shaft to which the feeder-arms are connected, a pivoted lever having a curved end connected to said rock-shaft by means of a crank and a cable, and projections on said sweep-head 45 adapted to engage the curved end of said lever, substantially as set forth.

7. In a baling-press, the combination of a baling-chamber, a hopper located over said chamber having slots in one end thereof, 50 feeder-arms pivoted back of said hopper and adapted to pass through the slots, brackets secured to the hopper and adapted to hold and guide said arms when in their upper positions, and means for moving said arms, substantially as set forth.

8. In a baling-press, the combination of a baling-chamber, a hopper located over the chamber, feeder-arms, a rock-shaft to which the feeder-arms are connected, a crank 60 secured to said rock-shaft and having a curved slot, a cable connecting with said arms by means of a clevis engaging in said slot, and means for moving said cable to operate said arms, substantially as and for the purpose 65 set forth.

WILLIAM R. COLMAN.

In presence of—

WILLIAM C. WHEELER,
OTTO H. HOFFMAN.
